UNITED STATES PATENT OFFICE.

GEORGE S. GATCHELL, OF ROSELLE PARK, NEW JERSEY, ASSIGNOR TO THE SINGER MANUFACTURING COMPANY, OF ELIZABETH, NEW JERSEY, A CORPORATION OF NEW JERSEY.

LOOPER-THREAD-CONTROLLING MECHANISM.

Application filed March 27, 1922. Serial No. 547,278.

To all whom it may concern:

Be it known that I, GEORGE S. GATCHELL, a citizen of the United States, residing at Roselle Park, in the county of Union and State of New Jersey, have invented certain new and useful Improvements in Looper-Thread-Controlling Mechanisms, of which the following is a specification, reference being had therein to the accompanying drawings.

This invention relates to looper-thread controller mechanism for chain-stitch sewing machines and has for an object to provide a to-and-fro moving or oscillatory thread-controller having operative characteristics approximating those of looper-thread controllers of the rotary type, thus affording satisfactory control of the looper-thread in machines having an oscillatory thread-controlling shaft, without the necessity of altering the driving mechanism for such shaft or changing the position of such shaft in the machine frame.

Looper-thread controllers of the type under consideration commonly comprise an intermittent looper-thread nipper, a take-up cam on the looper side of such nipper and a pull-off cam on the thread-supply side of such nipper. The take-up cam serves to control the slack in the looper-thread during the retraction of the looper-blade and to pay out looper-thread as the looper advances. The pull-off cam serves to provide a free supply of looper-thread for easy passage through the thread-nipper. It is customary to time the thread-nipper to hold the looper-thread as the looper-thread take-up pulls back the slack given up by the retracting looper, and to release the thread as the looper advances, thus permitting the latter to pull thread from the supply. Heretofore, in thread-controlling mechanism of the oscillatory type, the cam for closing the nipper during the retraction of the looper has also necessarily operated to close the nipper during the advance of the looper. This double closing of the nipper by the oscillatory nipper-cam is undesirable as, for best results, the looper-thread should be free to run through the nipper during the advance of the looper.

According to the present improvement, the nipper-operating cam has been reconstructed to operate when its shaft rocks in

one direction and to be ineffective when its shaft rocks in the reverse direction; the result being, that the nipper is closed but once during each stitch-forming cycle, i. e., during the retraction of the looper, and remains open during the entire advancing stroke of the looper.

In the accompanying drawings, Fig. 1 is a fragmentary side elevation, partly in section, of a machine embodying the invention. Fig. 2 is a plan view of the thread controller mechanism shown in Fig. 1. Figs. 3^a to 3^d, inclusive, illustrate the pull-off, thread-nipper, take-up and stitch-forming instrumentalities in their respective positions when the loopers are beginning their retracting stroke. Figs. 4^a to 4^d, inclusive, are similar views at a slightly later period in the cycle when the nipper is closed. Figs. 5^a to 5^d are similar views at the period in the cycle when the loopers are beginning their advance stroke. Figs. 6^a to 6^d are similar views at the period in the cycle when the advancing loopers have passed safely into the needle-loops. Fig. 7 is a diagram showing the action of the various thread-controlling instrumentalities on the thread at different periods in the cycle and Fig. 8 is a transverse sectional view through the nipper operating cam.

In the embodiment of the invention chosen for the purposes of the present disclosure represents the standard of a cylinder-bed machine of the usual type represented in the patent to Molyneux No. 1,111,167. The present machine has the usual transverse main-shaft 2 and suitable connections for operating the needles 3 and loopers 4 in the usual manner to sew two separate rows of double-chain stitches. The loopers 4 are mounted on the rocking and endwise sliding looper-shaft 5 which extends within and lengthwise of the cylinder-bed 6.

The looper-thread controlling mechanism is mounted on the usual rock-shaft 7 disposed within and transverse of the cylinder-bed 6 on the conical bearing pins 8. This shaft has fixed thereto a crank 9 which is connected by the pitman 10 to an actuating eccentric 11 on the main-shaft 2. The take-up cam is preferably shaped substantially as shown in Fig. 3^c and may comprise the twin-blades 12 between and at the sides of which are arranged the three thread-guiding arms

13; a double cam of this nature having substantially double the action on the thread as compared with a single cam.

The pull-off cam is shown at 14 and acts 5 on the thread between the thread-guiding arms 15.

Mounted on the shaft 7 between the cams 12 and 14 is the nipper operating device comprising a collar 16 to which is pivoted at 17 10 the rocking toggle element or cam-section 18 preferably having flat sides 19 and 20 adapted to contact respectively with the flattened surfaces 21 and 22 on the collar 16. The toggle element 18 is preferably formed 15 with a curved side 23 which is substantially concentric with the shaft 7 when the element 18 is in one of its extreme positions with the surfaces 20 and 22 in contact, Fig. 4^b. The curved side 23 is high enough to lift 20 the lower nipper-spring 24 into nipping relation with the upper nipper-spring 25.

The tilting element 18 is preferably formed with another curved side 26 which is substantially concentric with the shaft 7 25 when said element is in the other of its extreme positions, Figs. 3^b or 5^b, with the surfaces 19 and 21 in contact. The curved side 26 is not high enough to lift the lower spring 24 into nipping relation with the upper 30 spring 25 and rides under the nipper springs, during the return movement of the rock-shaft 7, Fig. 6^b, without closing such springs.

The curved sides 23 and 26 of the pivoted element 18 may meet to form an edge 27 35 which is so related to the spring 24 and to the centers of the pivot 17 and shaft 7 as to cause said element to be tilted from one extreme position to the other during the first part of the rocking movement of the 40 shaft 7 in either direction; said edge 27 and pivotal center 17 giving to the element 18 the character and function of a toggle element having a wiping engagement with the thread-nipper.

45 Referring to Figs. 3^a to 3^d, inclusive, the needles 3 are fully raised and the loopers 4 are fully advanced. The nipper-springs 24, 25 are open. The take-up and pull-off cams are out of engagement with the looper-thread. As the loopers dwell in their advanced position, the shaft 7 rocks sufficiently to tilt the toggle element or cam-section 18 from the position shown in Fig. 3^b to that shown in Fig. 4^b, thus closing the nipper at 50 about the time the take-up cam 12 and pull-off cam 14 engage the thread. As the loopers retract from the position shown in Fig. 4^a, the nipper remains closed and the cam-edge 28 on the take-up cam 12 in cooperation with 55 the thread-guides 13 absorbs the slack-thread given up by the looper. The cam 14 pulls thread from the supply. Before the loopers reach the end of their retracting stroke the thread slips over the hump 29 or high point 60 on the cam 12 and slack is thus afforded to

permit the loopers to move to the end of their retracting stroke. The nipper opens at about the time the thread slips over the hump 29. As the loopers execute the first part of their advancing stroke, Figs. 5^d to 7^a, the cam-edge 30 on the take-up cam 12 75 pulls back on the looper-thread and prevents buckling of the thread in front of the eyes of the loopers. When the loopers have passed safely into their respective needle-loops, Fig. 6^a, the thread slips over the hump 29 on the take-up cam and is free to be drawn upon by the loopers in advancing to the ends of their strokes. It will be observed 80 that the nipper remains open during the entire advance of the loopers.

The looper-threads pass through the usual guide-eyes in the looper-blades, thence through the eye 31 in the heel of the looper nearer the end of the arm 6 and then through 85 the usual thread-tube 32 to the thread-controlling devices on the shaft 7.

By the means described, the nipper is operated by an oscillatory shaft, yet is closed only during the retracting stroke of the 90 loopers; the timing being similar to that obtained by the use of a rotary nipper operating shaft.

Having thus set forth the nature of the invention, what I claim herein is:—

1. In a sewing machine, an oscillatory shaft, a thread-nipper, and a nipper operating toggle element pivotally connected to said shaft and having a wiping engagement with said thread-nipper.

2. In a sewing machine, in combination, a thread-nipper, an oscillatory shaft, a nipper operating element pivoted eccentrically on and tiltably movable relative to said shaft, and means for limiting the tilting movement 105 of said element.

3. In a sewing machine, in combination, a thread-nipper, an oscillatory shaft, and a nipper operating element pivoted eccentrically on said shaft for rocking movement 110 between predetermined limits relative to the latter, said element being adapted to alternately assume effective and ineffective positions as said shaft oscillates.

4. In a sewing machine, an oscillatory shaft, a thread-nipper, and a thread-nipper operating cam mounted on and movable relative to said shaft, said cam having high and low faces which act alternately upon 115 said nipper to close the latter during the oscillation of said shaft in one direction only.

5. In a sewing machine, an oscillatory shaft, a thread-nipper, a support secured to said shaft, a nipper-operating element pivotally mounted on said support, and means for limiting the range of pivotal movement of 125 said element relative to said support.

6. In a sewing machine, an oscillatory shaft, a thread-nipper, a collar secured to said shaft, and a nipper operating cam hav- 130

ing high and low faces and pivoted on said collar eccentrically of said shaft.

7. In a sewing machine, an oscillatory shaft, a thread-nipper, and a nipper-operating toggle element pivotally connected to said shaft, the center of said pivotal connection passing back and forth between the nipper and the center of said shaft.

8. In a sewing machine, an oscillatory shaft, a thread-nipper, a collar secured to

said shaft, and a nipper operating toggle element pivoted on said collar eccentrically of said shaft, the center of said pivot passing back and forth between the nipper and the center of said shaft as the latter oscillates.

In testimony whereof, I have signed my name to this specification.

GEORGE S. GATCHELL.
